UNITED STATES PATENT OFFICE.

ALFRED P. WARD, OF SAN ANTONIO, TEXAS.

FIREPROOF BUILDING CONSTRUCTION.

1,391,352.

Specification of Letters Patent. Patented Sept. 20, 1921.

Application filed October 1, 1917. Serial No. 194,220.

To all whom it may concern:

Be it known that I, ALFRED P. WARD, a citizen of the United States, and a resident of San Antonio, in the county of Bexar and 5 State of Texas, have invented a certain new and useful Improvement in a Fireproof Building Construction, of which the following is a specification.

The present invention relates to fireproof 10 building construction of that type wherein a "skeleton" frame of reinforced concrete or steel is usually erected, and wherein subsequently the walls and partitions are built around and over the "skeleton" frame.

15 The invention more particularly relates to that class of fireproof construction wherein knock-down forms are usually employed for setting up the cementitious parts, such as the columns and beams, and has for an object to provide an improved method and 20 means for producing permanent forms for retaining the cementitious columns and beams during their setting.

Another aim of the present invention is 25 to provide a building structure having cementitious parts, and having its permanent parts so initially assembled as to provide permanent forms for the cementitious parts.

30 The invention further aims at the provision of building and wall construction wherein the columns and beams may be molded and set directly into the wall structure so as to become firmly united thereto 35 and become, practically, an integral part thereof.

Another object of the present invention is to peculiarly construct a wall to provide the necessary forms, or the major portions 40 thereof, for retaining the columns and beams while setting, and by means of which the knock-down form may, to a large extent, be eliminated.

A still further object of the present invention is to provide a novel means for 45 supporting a cementitious beam directly against the wall elements while the beam is setting to cause the beam to mold itself into and become a part of the wall structure.

50 Various other objects and advantages of

this invention, as well as the above, will be more specifically brought out in the following detailed description of the present embodiment, the same being illustrated in the accompanying drawings wherein:

55

Figure 1 is a perspective view of a portion of a fire-proof wall constructed according to the present invention, and illustrating the arrangement of the parts to provide a mold or form for the cementitious 60 beams and columns adapted to form a part of the wall, the structure and arrangement being according to the present invention.

Fig. 2 is a horizontal section taken through the wall showing the permanent 65 parts thereof arranged to provide the forms for the cementitious columns, some of the forms being left open at their inner sides, and the dotted lines showing the proposed inner faces of the columns.

70

Fig. 3 is a similar view disclosing the wall structure subsequent to the application of the knock-down form sections, and the filling of the forms with cementitious material.

Referring to these drawings, wherein like 75 parts are indicated by similar numerals of reference throughout the several views, one form or type of wall is disclosed, the same being of the hollow tile structure.

The wall comprises a body portion formed 80 of a plurality of hollow tiles 10 which are assembled in abutting relating in the usual manner, and which are provided with a facing 11 of brick or the like.

From Fig. 2 of the drawings, it will be 85 noted that the tiles 10 are arranged in separate rows, the rows being spaced-apart endwise to provide therebetween spaces 12 of suitable width for accommodating columns 13 adapted to be formed between the spaced-apart ends of the tiles. When the column 13 is to be substantially rectangular in cross-section and to have the same depth and width, the tiles 10 arranged at the corner of the wall may be brought into contact at 90 their inner adjacent corners, as shown at 14 to entirely inclose the column space and provide a permanent form between the facing 11 and the body portion of the wall.

When, however, the columns are to be of 100

greater depth than the thickness of the tiles 10, and at those portions of the wall lying between the corners or angles thereof, knock-down forms 15, of wood or the like, are placed over the open inner side of the column-receiving openings to complete the inclosure.

The columns 13 are of any suitable cementitious material which may be poured into the column openings 13, and are preferably provided with vertical steel reinforcing rods 16 which are bonded together by the hooping 17, or the like, and about which is poured the cementitious mass for forming the columns.

When the height of a flooring has been reached, the laying up of the tile body is discontinued and the brick facing 11 is laid up to a height above the tiles 10 equal substantially to the thickness of the floor. The tiles 10 are now covered with a relatively heavy water-proofing paper 18 or other substance which is capable of supporting a cementitious mass on top of the tiles, and a knock-down or removable form board 19 is placed with its lower edge overlapping the inner faces of the topmost tiles 10 to form, above the body portion of the wall and on top of the supporting layer 18, a form or space between the board 19 and the facing 11. It will be noted from Fig. 1, that the columns 13 terminate at their upper ends substantially flush with the upper edges of the top row of tiles 10. However, the knock-down portions 15 of the column forms are continued upwardly and form a part of the mold board 19.

The board 19 and the form sections 15 are supported in any suitable well-known manner, and it is not deemed necessary to illustrate the supporting means in connection with this invention. The cementitious body is now poured into the space between the board 19 and the facing 11, and molds itself into the crevices between the bricks of the facing 11, and into the top of the uppermost row of tiles 10. This latter poured body of cementitious material, when set, provides supporting beams for the flooring, or the like, and causes the beams to conform to the top of the wall and to become a part of the vertical cementitious columns which have already been poured.

By thus first erecting the wall, and arranging the tile and brick units thereof in such relation as to provide permanent forms for the columns and beams, the latter are caused to mold into the permanent parts of the forms and become united integrally therewith.

It is of course understood that various changes and modifications may be made in the construction of the wall or building, and the tiles may be arranged in any suitable manner, the main object of the invention be-

ing to so arrange the tiles and the facing of the wall as to provide the permanent forms or openings into which the cementitious columns and beams may be poured. It is to be further understood that these changes and modifications are restricted only by the scope of the following claims.

I claim:

1. In wall construction, the combination of a plurality of tiles laid up with vertical spaces between the facing ends of certain of the tiles, a brick facing laid up against the outer sides of said tiles and across said vertical spaces to close the same, and poured cementitious elements molded in said spaces between the tiles and the brick.

2. In building construction, the combination of a plurality of tiles laid up with vertical spaces between the facing ends of certain of the tiles, a brick facing laid up against the outer sides of said tiles and across said spaces to close the same, said brick facing being extended above the top row of tiles, cementitious columns poured into said vertical spaces and molded against said tiles and bricks, and horizontal beams of poured cementitious material molded upon the top row of tiles and against the extended portion of said brick facing.

3. In wall construction, tiers of blocks formed of superposed individual blocks and the tiers being longitudinally spaced apart to provide vertical openings between adjacent ends of certain of the blocks and with said openings extending throughout the height of the wall, and a facing of brick arranged against the outer side of said tiers of blocks and across said openings to close the outer sides thereof, and poured columns of cementitious material filling said openings between the tiers of blocks and adhering to the adjacent blocks and to the inner faces of said bricks to provide supporting columns in the wall and to bind said blocks and said bricks together.

4. In building construction, the combination of a plurality of tiles laid up with vertical spaces between the facing ends of the tiles, a brick facing laid up against the outer sides of said tiles and across the spaces to close the same, said brick facing being extended above the top row of tiles, a layer of supporting material upon the upper faces of the uppermost of said tiles, cementitious columns poured into said vertical spaces and molded against said tiles and bricks, and horizontal beams of poured cementitious material molded upon said supporting layer above the top row of tiles and against the extended portion of said brick facing.

5. In a wall construction, tiers of blocks formed of superposed individual blocks, the tiers being longitudinally spaced apart to provide vertical openings extending the entire height of the tiers of blocks, and a

facing of brick arranged against the outer side of said tiers of blocks and across said openings to close said openings, and extending above said blocks to form a ledge, and
5 poured columns of cementitious material filling said openings between said tiers of blocks, and beams of cementitious material formed on the upper surface of the tiers of blocks and columns, the cementitious material adhering to the blocks and to said 10 facing of bricks to bind said blocks and bricks together.

ALFRED P. WARD.
